FOOT VALVE

Alexander Boynton, San Antonio, Tex.

Application November 28, 1938, Serial No. 242,775

13 Claims. (Cl. 103—234)

My invention relates to a method and means of lifting liquids from wells by utilizing the force of gaseous pressure fluid confined in the annular space between the well casing and the eduction tube to aerate the liquid in the eduction tube if the liquid level is comparatively high and, thereafter, when the liquid level has been lowered, to expel the same in slugs by successively and automatically admitting slugs of well liquid of predetermined weight into the eduction tube, and then admitting gaseous pressure fluid under each slug to expel it from the well by the force of expanding the gas.

One of the objects is to overcome the usual high starting or kickoff pressures otherwise required to initiate flow, to cheapen the operation, and to increase the production by employing air or gas at low pressures to expel the well liquid by slugging after the accumulated head has been discharged.

A further object is to maintain a relatively low gas-oil ratio by expelling slugs with a minimum of aeration.

A still further object is to provide means to maintain the highest possible "bottom hole pressures" consistent with the desired amount of liquid production in combination with the lowest gas-oil ratio obtainable, it being possible to adjust the air or gas pressure at a value that will cause the production to exactly equal a predetermined amount irrespective of whether the well is flowed with its own or input gas.

The construction, installed upon the lower end of an eduction tube within a well casing closed around the tube proximate the ground surface, employs two valves, one within the other. The inner valve seats upon the outer valve, the outer valve having impaired clearance within a tubular member and a seat upon another tubular member above it. A latch is employed to hold the inner valve yieldably seated against a predetermined force.

A weight is employed to hold the movable assembly of valves and latch in the lower position with the inner valve seated upon the outer valve until a predetermined pressure fluid force raises the movable assembly of valves, weight, and latch, and seats the outer valve, after which the inner valve is unseated by the force of well liquid and pressure fluid. Back pressure of well liquid then unseats the outer valve; whereupon all movable parts are returned to the lower position by force of the weight member which, in landing, springs the latch. The movable assembly is housed with-

in a tubular case through which well liquid and pressure fluid alternately flow.

Aerating devices may be spaced at intervals in the flow tubing to unload the well down to the level where this invention will function as a slugging means.

The invention consists in the construction, combination, and arrangement of parts hereinafter described, and claimed, and illustrated in the accompanying drawings in which:

Fig. 1 is a vertical section of a well equipped with this device installed within the bracketed space A, the inner portion of the device being shown in elevation.

Fig. 2 is a vertical section of the device with its working parts in the lower position.

Fig. 3 is mainly a vertical section of the device with its working parts in the upper position, the lower end thereof being shown in elevation.

Fig. 4 is a horizontal section on the line 4—4, Fig. 2.

Fig. 5 is a horizontal section on the line 5—5, Fig. 2.

Fig. 6 is a horizontal section on the line 6—6, Fig. 2.

Fig. 7 is a horizontal section on the line 7—7, Fig. 2.

Fig. 8 is a vertical section of a part of the device on the line 8—8, Fig. 5.

Fig. 9 is a horizontal section on the line 9—9, Fig. 2.

Fig. 10 is a vertical section of the lower end of the device shown in Fig. 3.

Fig. 11 is a horizontal section on the line 11—11, Fig. 2.

Fig. 12 is a vertical section of a portion of a modified form of the invention.

Fig. 13 is a horizontal section on the line 13—13, Fig. 12.

The same characters refer to the same parts throughout the several views.

The flow tubing connection 9, upper housing nipple 10, valve seat member 11, lower housing nipple 12, and anchor joint connection 13 form the outer shell within which the landing weight 28 normally lands its legs 28a upon the upper end of connection 13. The upper end of landing weight 28 is threadedly connected to latch housing nipple 19. This nipple is in turn threadedly engaged at its upper end to lower extension 17a of valve and valve seat member 17 having lateral openings 17b, valve seat 17c, and chamber 17d. The engagement between members 17 and 19 is secured by lock ring 18.

Within valve and valve seat member 17, valve

member 16 has a close working fit. Vertical passage 16d, within tubular section 16a, communicates with lateral openings 16b and 16c, the upper portion of member 16 being enlarged to form a valve which normally engages a valve seat 17c. Nipple 15, which may contain lead or other substance 15a to give it correct weight to cause the desired difference between the weight of the slug and the value of the pressure fluid, is threadedly connected to valve member 16 and to upper weight member 14 which has a four way finned extension 14a having an easily movable fit within the central opening through connection 9.

The lower end of valve member 16 has threaded engagement with latch shaft 20, the upper portion of which has a close working fit through a central opening within extension 17a. The central enlarged portion of shaft 20 has a free sliding clearance within the central opening through ball roof 23; and the lower end has a close sliding fit in the central vertical passage 28c in the upper end of member 28. Upon the threaded portion of shaft 20, ball floor 26 is engaged and secured by lock nut 27. Spacer pipe 22, the upper end of which has a free sliding fit within the central opening in threaded extension 17a, is threadedly joined to the cupped upper end of ball roof 23. Latch spring 21 has clearance over nipple 22 and free clearance between it and the wall of nipple 19. This spring, installed somewhat compressed, is held in a fixed position at its upper end by the lower end of extension 17a. The lower end of this spring rests upon the upper end of ball roof 23.

The expansive force of compressed spring 21 impinges latch balls 25 between the oppositely inclined adjacent surfaces of ball roof and floor urging the balls outward against latch sleeve 24, which may be pressed into nipple 19 and landed upon a shoulder 19a as shown. The opening through sleeve 24 is of such diameter as will force the latch balls inwardly, somewhat less than one half the diameter of the balls from their extreme outer position at either end of the latch travel. The longitudinal peripheral slots 24a serve to allow free movement of the lubricant within the latch chamber in order to prevent partial impingement upon the lubricant in the downward stroke of the movable parts within the latch.

The position of the latch balls can be adjusted vertically by screwing the ball floor 26 upward or downward on shaft 20, and the vertical travel of the latch may be regulated by slightly lengthening or shortening spacer nipple 22 which, at the upper end of its travel, lands upon the member 17. The length of nipple 22, in addition to governing the latch travel, also stops valve member 16 in proper position to allow fluid to pass through it without abrading valve seat 17c, as appears in Fig. 3. In latching the balls roll part way over the ends of sleeve 24 as is apparent, the balls being held from escaping outwardly by the peripheral cupped portion of the roof and floor, as appears, provision being also made for some clearance between the balls and shaft 20 at the extreme inward position of the balls as they pass through sleeve 24. The latch chamber within nipple 19 should be filled with a lubricant, the escape of which is prevented by the close fit of shaft 20 within the bore at either end.

Manifestly, the latching force is governed by the compression energy of spring 21, and by the 75

extent of the outward travel of the latch balls over the curved ends of sleeve 24.

It can be observed that the lower end of shaft 20, movable within the bore 28c, serves to maintain the displacement of this shaft within the latch chamber at a constant value; that is, when the shaft moves upward, the lower end of the shaft is entering the chamber as the upper end is leaving, and vice versa. Therefore, the latch chamber within nipple 19 does not breathe during the movements of the latch. Manifestly, to accomplish this constant displacement, both ends of the shaft must be of the same diameter as shown.

The mechanism above described is installed within the bracketed space A, Fig. 1, by threadedly joining flow tubing connection 9 to the lower end of the flow tubing. Perforated anchor support 2b, closed by cap 2c, may extend to the bottom of the well B and support the flow tubing.

Pressure fluid to operate the device is confined in the annular space 1a between the flow tubing 2 and well casing 1. This fluid may be 25 gas originating within the well or may be supplied from an external source through nipple 8. The necessary seal between the flow tubing 2 and well casing 1, proximate ground surface G, is accomplished in Fig. 1 by casing head base 30 3, cap 4, plate 5, seal ring 6, weld 5a, and bull plug 7, as is old and obvious.

One or more aerating devices 2a, such as is described in either of my following patents: 1,470,053, 1,517,611, 1,686,262, 1,712,418, 1,747,- 35 570, 1,747,571, 1,747,572, 1,749,124, 1,767,201, 1,767,202, 1,768,109, 1,768,110, 1,770,023, 1,772,036, 1,773,942, 1,773,943, 1,779,726, 1,779,727, 1,784,720, 1,793,671, or 1,952,581 may be placed in the flow 40 tubing at intervals of approximately 100 to 500 feet, depending upon the well condition and value of the pressure fluid used in flowing the well. The use of such aerating devices reduces the initial pressure required to unload the well down to proximate the level of the device disclosed in 45 this application.

The operation of this invention, after the accumulated head of well liquid has been discharged from the well above transverse passages 28b by the combined action of the aerating devices 2a and this invention will now be briefly described. It is assumed that air or gas of sufficient volume and pressure to flow the well is confined in the annular space 1a between the well casing and flow tubing. The movable assembly is at rest in the lower position shown in 50 Fig. 2.

Air or gas in the annular space between well casing and flow tubing follows the previously 55 expelled well liquid into the flow tubing. The velocity of the air or gas entering the flow tubing via perforations 12a, 12b, and through the central opening in connection 13 passing into the eduction tube by flowing around member 17, through the annular space exterior of nipple 15 and weight member 14, and between fins 14a, increases rapidly as the last of the accumulated well liquid is expelled from the flow tubing. The lifting force of this pressure fluid, accompanied by a certain amount of well liquid in spray form, quickly lifts the movable assembly because of the resistance offered to the pressure fluid and liquid spray in passing through the restricted annular clearance between valve 17 and nipple 12, some additional lifting resistance being also developed in the less restricted annular space

around members 14, 15, 19, and 28. Valve surface 17e seats upon its seat 11a, thus stopping, for the time being, further escape of pressure fluid and well liquid through the flow tubing. The movable assembly is now in the position shown in Fig. 3, except that valve 16 is still seated in the position shown in Fig. 2. Well liquid now comes into the well from the producing formation through perforations P. Pressure fluid, at the same time, is entering and building up pressure within the annular space 1a, the operation of the device being identical whether the well produces enough gas to flow it or whether pressure fluid is partially or entirely supplied from an external source through nipple 8.

When the pressure of the well liquid entering through openings 17b, under inner valve member 16, plus the air or gas pressure in the annular space 1a builds up to a predetermined value the latch will be sprung and valve 16, nipple 15, and weight member 14 will be quickly raised to the position shown in Fig. 3.

Part of the pressure that held valve 17 seated in its upper position, shown in Fig. 3, is now exerted above this valve due to the flow of well liquid through chamber 17d, lower lateral openings 16c, vertical passage 16d, and upper lateral openings 16b into the flow tubing above. The pressure thus exerted above seated valve member 17 partially neutralizes the force that theretofore held this valve seated. The entire movable assembly, therefore, falls. In falling valve 16 remains open as shown in Fig. 3, until weight 28 lands upon connection 13. The impact of this fall springs the latch, from its upper to its lower position, completing the operating cycle and returning all movable parts to the position shown in Fig. 2.

Briefly summarized, valve 17 is seated by air or gas pressure and is unseated by fluid back pressure. Valve 16 is unseated by liquid pressure plus air or gas pressure, and is seated and latched by impact of the falling weight.

The falling movement of the movable assembly is made more forceful by passages 12b, proximately below valve seat 11a, due to the fact that the restricted clearance around valve seat member 17 (.010" to .025" being workable) makes openings 12b the path of least resistance from the annular space 1a into the flow tubing. As soon as the falling movement begins, the increased pressure above member 17, due to the inrush of well liquid through openings 12b, causes the movable assembly to fall with increased velocity. To make sure that the movable assembly will fall freely, it will be observed that the aggregate cross sectional area of perforations 12a immediately above connection 13, plus the cross sectional area of the vertical opening through connection 13, is considerably greater than the cross sectional area of valve member 17. This provides for free displacement of liquid by the movable assembly as it falls.

In order to assure that the landing impact will always spring the latch to close valve 16, the construction should preferably allow the movable assembly to fall 1-5 feet.

Perforations 12b should be large enough to admit the well liquid fast enough to allow the desired rate of production, but these holes must not be so large as will cause the back pressure of gas escaping through the flow tubing following the slug to prevent valve 17 from seating.

2-4 holes, each $\frac{1}{8}$ " to $\frac{3}{16}$ " diameter, will be found approximately correct for 2" flow tubing.

It will be observed that the greater the weight value of weight member 14 and nipple 15, and the greater distance the movable assembly falls when valve 17 unseats, the greater will be the force of the impact when the landing weight strikes connection 13.

It will also be observed that the latch can be made to hold with different forces in the upper and lower positions, by allowing the latch balls to roll farther outward for more latching force, and vice versa, as before stated. Thus any desired value of fluid force can be caused to open valve 16, and a much lesser force can be made to close it by the landing impact.

Obviously, the force with which the latch holds, when the balls are engaged upon the upper curved surface of sleeve 24, must be such that the landing impact will spring the latch when the movable assembly falls. The device will often function better with the latch entirely unengaged at the top. It is also apparent that the greater the force with which the latch holds when the balls are engaged upon the lower curved surface of sleeve 24, the greater must be the sum of the liquid and pressure fluid force required to spring the latch in order to open valve 16, thereby admitting the slug into the flow tubing.

The latch must be adjusted to hold valve 16 seated with such force that the combined pressure of the slug (still in the annular space 1a) and the pressure fluid will be required to spring the latch, unseating valve 16. Reducing the air or gas pressure in the annular space 1a will, therefore, increase the weight of liquid required to open the valve 16, and consequently increase the weight of the slug to be expelled. Corollarily, increasing the air or gas pressure will lighten the slug.

It should be further observed that the air or gas pressure per square inch within the annular space 1a should be somewhat greater than the pressure per square inch at the base of the slug when it has entered the flow tubing. If the slug pressure at its base should be greater than the force of the pressure fluid, the aerating devices 2a will have to flow out of the upper portion of the slug before the remaining portion will be expelled. Such a flowing condition indicates that the air or gas pressure should be increased until the slugs occur at regular intervals, and are expelled without appreciable aeration.

If the slugs are too short to afford a satisfactory gas-oil ratio, the air or gas pressure should be reduced until the weight of the slugs is such that the air or gas pressure will expel them at such intervals as will keep the well liquid head down low enough to allow the device to produce by slugs, unaided by the aerating devices 2a, the latter being properly employed only to unload the well after a period of standing. If the production of the well is so great that this result cannot be attained with the device as installed, the latch should be adjusted to hold valve 16 seated with greater force. Such adjustment will increase the weight of slugs admitted, and proportionately increase the volume of liquid delivered into the flow tank.

Obviously, increasing the holding force of the latch in seating valve 16 will also permit the use of air or gas at greater pressure.

If aerating devices 2a are employed to initially unload the well, a type of aerating device that

is operated by liquid pressure such as described in my Patent No. 1,952,581 will be found to afford a better gas-oil ratio than the differential type of such devices. If aerating devices of the type here recommended are employed, they should be adjusted to intake air or gas into the flow tubing at a pressure within them of slightly greater value than the pressure used to flow the well by slugs. Such devices will not then admit air or gas from the annular space $1a$ to enter the flow tubing as the slugs pass by them, but they will remain inoperative while the device is expelling slugs. Such employment of said aerating devices will, however, require that air or gas at a slightly higher pressure be used to unload the accumulated production than will subsequently be required to operate this slugging device.

Fig. 12 shows that a spring 29 , freely movable within nipple 10 , may be substituted for the weight member 14 in Figs. 2, 3 and 8. The spring, installed under some compression, is held against flow tubing connection 9 by the finned support 30 threadedly engaged upon nipple 15 . If a spring is used instead of a weight member, the free length of spring should be at least 10 times greater than the travel of the movable assembly and should be installed compressed at least 50% of its free length, in order that the expansion force of the spring will not become unduly spent before the movable assembly is returned to its lower position.

It will be understood that the foregoing drawings and specification are illustrative and not intended to limit the construction or uses of this invention which may be greatly varied within the scope and purpose thereof.

I claim:

1. A foot valve for wells to control the periodic discharge of slugs of liquid including, an eduction pipe, a freely movable valve assembly closely fitted therein and adapted to be raised when the resistance to the flow of fluid through the pipe is sufficiently reduced, a seat to be engaged by said assembly to close the pipe, and a valve within said assembly to thereafter open upon the accumulation of a predetermined pressure therebelow so as to release the accumulated pressure thru said assembly whereby the assembly will drop away from said seat and the rate of flow will again increase until the resistance to flow again raises the assembly.

2. A control valve for wells including, an eduction tube, a seat therein, a valve to be raised against said seat by the flow of fluid when the back pressure due to liquid in the eduction tube above said seat is decreased to a predetermined value so that the eduction tube is closed, and means operable upon the building up of a predetermined pressure below said valve to release such pressure thru the valve so that the valve will move from the seat by gravity and the increase of the back pressure in the tube due to the flow of liquid thru said means and past said valve.

3. A control valve for wells including, an eduction tube, a seat therein, a valve to be raised against said seat by the flow of fluid when the back pressure due to liquid in the eduction tube above said seat is decreased to a predetermined value so that the eduction tube is closed, and means operable upon the building up of a predetermined pressure below said valve to release such pressure thru the valve so that the valve will move from the seat by gravity and the increase of the back pressure in the tube due to the flow of

liquid thru said means and past said valve, and additional means to latch said first means to open only at said predetermined pressure below said valve.

4. A control valve for wells including an eduction tube, a seat therein, a valve to be raised against said seat by the flow of fluid when the back pressure due to liquid in the eduction tube above said seat is decreased to a predetermined value so that the eduction tube is closed, and means operable upon the building up of a predetermined pressure below said valve to release such pressure thru the valve so that the valve will move from the seat by gravity and the increase of the back pressure in the tube due to the flow of liquid thru said means and past said valve, and additional means to latch said first means to open only at said predetermined pressure below said valve, said last means being adjustable to vary the rate of operation.

5. A foot valve including a valve, a second valve movable therein, and latch means to hold said second valve in either closed or open position to cut off or allow a flow of fluid thru said first valve.

6. A foot valve including a valve, a second valve movable therein, and latch means to hold said second valve in either closed or open position to cut off or allow a flow of fluid thru said first valve, said means including a ball and sleeve latch.

7. A foot valve including a valve member, a second valve member movable therein, and latch means to hold said second valve member in either closed or open position to cut off or allow a flow of fluid thru said first valve member, and a weight member on said second valve member tending to close said second valve and open said first valve member.

8. A foot valve including a valve member, a second valve member movable therein, and latch means to hold said second valve member in either closed or open position to cut off or allow a flow of fluid thru said first valve member, and spring means on said second valve member tending to close said second valve and open said first valve member.

9. In a slugging foot valve for wells, the combination of a well casing having well liquid therein, an eduction tube extending into said liquid, sealing means between said tube and casing proximate the upper ends thereof, pressure fluid above the well liquid, means for replenishing said pressure fluid, an annular plate proximate in the lower end of said tube and transverse thereof, said plate having a central opening for the alternate admission of well liquid and pressure fluid, a valve assembly in said eduction tube, said assembly normally resting upon said plate, a valve seat in said eduction tube, said seat being in spaced relation to said assembly, an annular valve of said assembly engageable with said seat and having an impaired clearance therearound for pressure fluid to exert lifting force thereon to raise said valve to engage said seat at a predetermined velocity of said fluid, an axial opening in said valve, said opening having pressure ports communicating with the exterior thereof below the impaired clearance area and an annular valve seat surrounding the upper end of said axial opening, a second valve within said last axial opening and adapted to engage the seat around said opening, said second valve being adapted to be opened by combined force of well liquid and pressure fluid so that said liquid and fluid may

flow therethrough and to be closed by impact of said assembly upon said annular plate after the force of such well liquid becomes increased to a predetermined value in the eduction tube above said valves, a weight assembly extending upward from said second valve, a shell extending downward from said first valve, a weight upon said shell, lateral openings in said eduction tube below said seat to influence the movements of said assembly by apportioning the rate of fluid flow into said tube above and below said first valve, and lubricated latching means within said shell, said means being adapted alternately to support said second valve in closed and open positions.

10 15 20 25 30 35 40 45 50 55 60 65 70

10. In a slugging foot valve for wells, the combination of a well casing having well liquid therein, an eduction tube extending into said liquid, sealing means between said tube and casing proximate the upper ends thereof, pressure fluid above the well liquid, means for replenishing said pressure fluid, an annular plate proximate the lower end of said tube and transverse thereof, said plate having a central opening for the alternate admission of well liquid and pressure fluid, a valve assembly in said eduction tube, said assembly normally resting upon said plate, a valve seat in said eduction tube, said seat being in spaced relation to said assembly, an annular valve of said assembly engageable with said seat and having an impaired clearance therearound for pressure to exert lifting force thereon to raise said valve to engage said seat at a predetermined velocity of said fluid, an axial opening in said valve, said opening having pressure ports communicating with the exterior thereof below the impaired clearance area and an annular valve seat surrounding the upper end of said axial opening, a second valve within said last axial opening and adapted to engage the seat around said opening, said second valve being adapted to be opened by combined force of well liquid and pressure fluid so that said liquid and pressure fluid may flow therethrough and to be closed by impact of said assembly upon said annular plate after the force of such well liquid becomes increased to a predetermined value in the eduction tube above said valves, a weight extending upward from said second valve, a shell extending downward from said first valve, lateral openings in said eduction tube below said seat to influence the movements of said assembly by apportioning the rate of fluid flow into said shell above and below said first valve, and latching means within said shell, said means being adapted alternately to support said second valve in closed and open positions.

11. In a slugging foot valve for wells, the combination of a well casing having well liquid therein, an eduction tube extending into said liquid, sealing means between said tube and casing proximate the upper ends thereof, pressure fluid above the well liquid and means for replenishing said pressure fluid, an annular plate proximate the lower end of said tube and transverse thereof, said plate having a central opening for the alternate admission of well liquid and pressure fluid, a valve assembly in said eduction tube, said assembly normally resting upon said plate, a valve seat in said eduction tube, said seat being in spaced relation to said assembly and having an impaired clearance around the valve of said assembly for pressure to exert lifting force thereon to raise said valve to engage said seat at a predetermined velocity of said fluid, an axial opening in said valve, said opening having pressure ports communicating with the exterior

thereof below said impaired clearance and an annular valve seat surrounding the upper end of said axial opening, a second valve within said last axial opening and adapted to engage the seat around said opening, said second valve being adapted to be opened by combined force of well liquid and pressure fluid so that said liquid and fluid may flow therethrough and to be closed by impact of said assembly upon said annular plate after the force of such well liquid becomes increased to a predetermined value in the eduction tube above said valves, a weight extending upward from said second valve, lateral openings in said eduction tube below said seat therein to influence the movements of said assembly by apportioning the rate of fluid flow into said tube above and below said first valve, and latching means within said shell, said means being adapted alternately to support said second valve in closed and open positions.

12. In a slugging foot valve for wells, the combination of a well casing having well liquid therein, an eduction tube extending into said liquid, sealing means between said tube and casing proximate the upper ends thereof, pressure fluid above the well liquid, means for replenishing said pressure fluid, an annular plate proximate the lower end of said tube and transverse thereof, said plate having a central opening for the alternate admission of well liquid and pressure fluid, a valve assembly in said eduction tube, said assembly normally resting upon said plate, a valve seat in said eduction tube, said seat being in spaced relation to said assembly, an annular valve of said assembly engageable with said seat, impaired clearance around said valve for pressure fluid to exert lifting force thereon to raise said valve to engage said seat at a predetermined velocity of said fluid, an axial opening in said valve, said opening having pressure ports communicating with the exterior thereof below said impaired clearance, an annular valve seat surrounding the upper end of said axial opening, a second valve within said last opening and adapted to engage the seat around said opening, said second valve being adapted to be opened by combined force of well liquid and pressure fluid so that said liquid and fluid may flow therethrough and to be closed by impact of said assembly upon said annular plate after the force of such well liquid becomes increased to a predetermined value in the eduction tube above said valves.

13. A slugging foot valve for wells comprising in combination a well casing having well liquid therein, an eduction tube in said casing to provide an annular space, said tube extending into the liquid, an annular space between said tube and casing above such liquid, pressure fluid in said space, a seat in said tube, two valves, one within the other, the first of said valves being adapted to engage said seat, the second of said valves having a weight thereon and being adapted to seat upon said first valve, pressure fluid being employed to seat said first valve to close the eduction tube, the well liquid co-acting with the pressure fluid being employed to unseat said second valve to open said eduction tube, means to apply the weight of well liquid at a predetermined value to unseat said first valve, said second valve being seated by the falling impact of said valve and said weight to alternately admit slugs of well liquid and pressure fluid to said eduction tube and expel said liquid therefrom.
